BREAKER AND DISTRIBUTOR HEAD

Victor W. Thomas, Waukegan, Ill., assignor to
 Edward A. Harrington, trustee, Waukegan,
 Ill.

Application November 15, 1934, Serial No. 753,160

1 Claim. (Cl. 200—22)

My present invention relates to the provision of a new and improved breaker and distributor head for ignition systems for internal combustion engines, and has for its object the provision of instrumentalities in a breaker and distributor head which are caused to function by change in engine speeds for advancing and retarding the spark and for altering the action between the cam and the breaker so that the time during which the primary circuit is opened and closed will remain substantially the same at different engine speeds.

I have attained the above object by means of the structure and arrangement disclosed in the accompanying drawings, in which—

Fig. 1 is a top plan of a breaker head with the distributor cap removed.

Fig. 2 is a vertical elevation and section on line 2—2 of Fig. 1.

Fig. 3 is a plan of the breaker casing with the distributor cap and breaker plate removed.

Fig. 4 is a central vertical section on line 4—4 of Fig. 1, the breaker arm and contact and condenser being omitted for clearness.

Similar reference characters refer to similar parts throughout the respective views.

The stem 5 of the breaker head is centrally bored for the passage of and to form a journal for the spindle 6. Preferably cast integrally with the top of the stem 5 is the casing 7. The casing 7 is de-centered with respect to the stem 5. The axis of the shaft or spindle 6 is indicated in Figs. 1 and 3 by the reference character X, while the center axis of the casing 7 is indicated in the same figures by the reference character Y. Adjacent the top of the casing 7 are provided annular grooves forming the shoulders 8 and 9. The breaker plate 10 rests and rotates upon the shoulder 8 and has an aperture 11 in its center of sufficient extent to permit the breaker plate to be rotated about the portion of the spindle or shaft 6 which projects therethrough. The top of the spindle 6 which extends into and above the compartment in the casing 7 is slightly reduced, and secured upon the shoulder provided by this reduction by means of a nut 12 is a worm wheel 13. Above the breaker plate 10 the spindle or shaft 6 is again reduced, and seating upon the shoulder thus provided is the cam 14 and an upstanding head 15, which is adapted to receive the distributor rotor (not shown). Any suitable means may be employed for securing the cam 14 and head 15 to the shaft 6 and I have illustrated an expanding screw 16 for this purpose, which cooperates with the bored and split upper end of the spindle or shaft. This is not an unusual

construction, and I have merely shown the expanding screw 16 thereof. The above described construction can be most clearly seen in Fig. 4.

Referring now more particularly to Fig. 1 it will be seen that fixed to the breaker plate 10 and extending upwardly therefrom is a post 17 carrying an insulating bushing 18 upon which is mounted a breaker arm 19. Intermediate of its length the breaker arm 19 is provided with a striker or rubbing block 20 for engagement with the points of the cam 14. A bracket 21 is also fixed to and insulated from the breaker plate 10 and secured to the bracket 21 is one end of a spring 22, the other end whereof is secured to the breaker arm 19 by means of the screw 23, 15 which also serves to secure the striker or rubbing block 20 thereto.

In automobile ignition systems it is usual to ground one terminal of the battery, and I have shown a conductor 24 from the battery terminal 20 which is not grounded, leading up through a suitable aperture in the breaker plate 10, and secured to the bracket 21 and in electrical connection with the spring held thereby. I have also shown a conductor 25 leading from one side of 25 the condenser 26 to the bracket 21. Upon the outer or unattached end of the breaker arm 19 is the movable contact 27, and secured to an adjustable bracket 29 is the adjustable fixed contact 28 which co-operates with the movable contact 27. The construction, purpose and manner of adjustment of the bracket 29, and also the means herein described for securing uniform electrical operation at divers speeds, were first disclosed by me in application for patent which has 35 been assigned Serial No. 744,386.

The breaker casing 7 is cast with a hollow development 30, the axis of which is parallel with a tangent to the worm wheel 13, and opposite the development 30 in the casing 7 is provided 40 an integral block 31 which is bored to provide a journal for the reduced end of a shaft 32, the opposite end whereof is journaled in a bore in the outer end of the development 30. A screw plug 33 is provided in this bore with a ball 34 45 for adjusting the shaft 32 in its respective journals.

Fixed to the shaft 32 is a worm gear 35 which meshes with the worm wheel 13. Also fixed to the shaft 32 is a collar 36, and slidably mounted 50 upon the shaft 32 is a collar 37, the hub of which is extended and provided with an annular slot 38. Extended between the peripheries of collars 36 and 37 are a plurality of thin, flexible spring straps 39, secured to the centers of which straps 55

are weights 40. Extending from the bottom of the chamber in the casing 7 is a stud 41 which is centrally bored for the receipt of a pin 42 which constitutes the fulcrum of a curved lever arm 43, in one end of which lever arm is fixed a pin 44 which extends into the annular channel 38 of the collar 37. The opposite end of the lever arm 33 is provided with an elongated slot through which projects a pin 45 fixed to and extending downwardly from the breaker plate 10.

As will be seen by reference to the co-pending application heretofore referred to the rotation of the plate 10 about the center Y will carry the striker or rubbing block 20 nearer to or farther from the axis X of the shaft or spindle 6 and cam 14, and that by changing the above noted relation the portions of the revolution of the cam, during which the primary circuit is closed and opened, are also changed. That is, when the apparatus is in retarded spark position and the engine is idling and the cam rotating at a relatively slow speed the portion of the cam engaging the striker or rubbing block 20 is of less extent than when the spark is advanced and the engine or shaft or spindle 6 is rotating more rapidly. The breaker plate is held rotatably upon its shoulder 8 by the heads of the screws 46 and the apparatus is set so that when the engine is idling or going at its slowest speed and the flexible straps 39 are most nearly straight, the rubbing block 20 is at the proper distance from the center X to give the desired current through the primary circuit. As the speed increases the weights 40 are carried outwardly by centrifugal force, which causes the flexing of the straps 39 and the drawing of the collar 37 toward the collar 36. The pin 44, working in the groove 38,

swings the lever arm 43 upon its fulcrum 42 and rotates the breaker plate 10 by moving the pin 45, which secures, at the same time, the advancement of the spark and the shortening of the time during which the primary circuit is closed. Upon a reduction of speed of the engine the flexible spring straps 39 will straighten out and the above described operation will be reversed.

By means of suitable measuring devices it will be found that this device will secure the advancement and retarding of the spark uniformly with the change of engine speeds and that the current flowing in the primary circuit will remain substantially constant at all engine speeds.

Having described my invention what I claim is new and desire to secure by Letters Patent is:

A breaker for ignition systems for internal combustion engines comprising a shaft, a cam mounted upon said shaft, a breaker plate mounted for movement about said shaft upon an axis eccentric to the axis of said shaft, a breaker arm mounted upon said breaker plate in co-operative relation with said cam, a fixed contact mounted upon said breaker arm, a worm wheel mounted upon said shaft, a shaft mounted with its axis at right angles to the axis of the shaft carrying said worm wheel, a worm gear mounted on said last mentioned shaft in co-operative relation with said worm wheel, a collar fixed upon said last mentioned shaft, a collar slidably mounted upon said last mentioned shaft, a plurality of flexible spring straps connecting said collars, weights mounted intermediate the ends of said straps and a linkage between said movable collar and said breaker plate.

VICTOR W. THOMAS.
